UNITED STATES PATENT OFFICE

WILLOUGHBY F. HOLLISTER, OF COWEN, WEST VIRGINIA

TANK CAP LOCK

Application filed March 22, 1930. Serial No. 438,155.

The invention relates to a new and improved lock for the filling neck cap of a conventional automobile fuel tank. The invention relates particularly to assemblages in which the filling neck of the tank is provided with opposed arcuate flanges of substantially right angular cross section extending inwardly from the outer end of the neck and having inclined edges which co-act with a pair of arms on the cap, for the purpose of securing the latter to the neck when said cap is turned in the proper direction.

It is one object of the invention to provide the aforesaid flanges with ratchet teeth and to mount a spring-pressed dog on the cap for coaction with said teeth in holding the cap against being turned in a direction to remove it, releasing means being provided for the dog, operable from the exterior of the cap.

The dog-releasing means is preferably key-actuated and it is a further aim to provide novel means for holding the above-named dog in its released position after it has once been released by the key, novel provision being made whereby the means for holding the dog in said released position may itself be released when it is desired to again have the dog project to operative position.

A still further object of the invention is to provide a new and improved lock structure of simple and inexpensive nature and one which may have fields of use other than in connection with tank caps.

With the foregoing in view, the invention resides in the novel subject matter herein-after described and claimed, description being accomplished by reference to the accompanying drawings.

Fig. 1 is a perspective view showing a portion of a fuel tank and the invention applied to the filling cap thereof.

Fig. 2 is a horizontal sectional view on line 2-2 of Fig. 1.

Fig. 3 is a vertical sectional view on line 3-3 of Fig. 2.

Fig. 4 is a horizontal sectional view on line 4-4 of Fig. 3.

Fig. 5 is a vertical section on line 5-5 of Fig. 2.

Fig. 6 is a disassembled perspective view of a number of the lock parts.

Fig. 7 is a horizontal sectional view showing the lock applied to a door.

The construction illustrated in Figs. 1 to 55 6 will first be described. In these views, T denotes a fuel tank of an automobile, said tank having a filling neck N provided with a flanged cap C. The outer end of the neck N is provided with opposed arcuate inwardly 60 projecting flanges F of substantially right angular cross section, said flanges having free inclined edges E which are co-operable with two arms A carried by the cap, for the purpose of securing the latter to the neck. These 65 arms are integral with a central plate P which is secured within the cap C in a conventional manner as illustrated in Fig. 5. When the cap is applied, the arms A pass through the gaps G between the flanges F and 70 then upon turning of the cap in the proper direction, said arms engage the edges E and draw the cap firmly into position and securely hold it.

All of the parts so far described are of 75 well known form and constitute no part of the present invention except in relation with new features hereinafter described.

I provide the flanges F with ratchet teeth 8 at their inner sides and mount a spring-pressed dog or bolt 9 on the cap C for engagement with said teeth for the purpose of holding the cap against turning in a direction to remove it. The dog or bolt could be of any desired form and any appropriate operating means could be provided for releasing said dog or bolt to allow removal of the cap. The preferred construction however has been illustrated and will now be described.

A sleeve 10 projects centrally outward from the cap C and is preferably secured to the plate P as illustrated in Figs. 3 and 5. A lock body 11 in the form of a block, lies against the inner side of the plate P and is itself provided with an outwardly projecting sleeve 12 90 which passes through the sleeve 10. A collar 13 is shown on the outer end of sleeve 12 abutting the outer end of sleeve 10 to hold the former against inward sliding from the latter, and to hold said sleeve 12 and the body 95 100

11 against rotation, a rivet or the like such as 14 of Fig. 5 may be employed.

The body 11 is provided with an opening 15 alined with and communicating with the sleeve 12, and at one side of said opening, 5 said body is provided with appropriate guides 16 and 17 for the bolt 9. At the opposite side of the opening 15, body 11 is formed with a lug 18, said lug and the aforesaid guides 16 10 and 17 being all disposed at the inner side of said body.

The bolt 9 is provided with a beveled tooth 19 adapted to co-act with a spring arm 20 for the purpose of holding said bolt in retracted 15 position, said spring arm being secured to the lug 18 and lying against the inner side of said bolt. An appropriate spring 21 is provided for normally projecting said bolt, and in the present disclosure, said spring is 20 housed within the bolt and abuts a pin 22 carried by the body 11 and the guide 17, the bolt being slotted at 23 to receive said pin. Projection of the bolt, if not limited by contact with one of the flanges F, is limited by 25 a stop stud or the like 24 with which it is provided, said part 24 being adapted to abut the guide 16.

A rotatable and slidable, key-actuated spindle 25 is shown for releasing the bolt 9, 30 the inner end of said spindle having a pinion 26 meshing with rack teeth 27 on one edge of said bolt. I have shown a sleeve 28 surrounding and secured to the spindle 25, said sleeve being slidable and rotatable within the 35 sleeve 12 and the opening 15. A screw 29 (Fig. 5) is illustrated for securing the parts 25 and 28 together, but other desired means could be provided for this purpose, and if desired, any appropriate arrangement of key- 40 controlled tumblers could be employed for normally locking the spindle against rotation. For illustrative purposes, however, the spindle 25 and the sleeve 28 are merely shown as provided with registering slots 30 and 31 to receive an operating key. It will be observed 45 that the inner end of the groove 30 is closed and that the inner end of the spindle 25 lies against the spring arm 20. Hence, after this 50 spring arm has engaged the tooth 19 of the bolt 9 to hold the latter retracted, an inward push on the key or perhaps directly upon the spindle, will inwardly spring said arm 20 from engagement with said tooth 19, allowing the bolt to again be projected under the 55 influence of its spring 21.

A cap 32 is preferably provided to normally protect the outer end of the lock structure. In the present showing, this cap is threaded upon the outer end of the sleeve 10, 60 but it might of course be mounted in some other appropriate way. At 33, the cap 32 may be provided with a vent for allowing entrance of air to the fuel tank as the fuel is withdrawn.

65 Upon removal of the cap 32 and insertion

of the proper key into the groove and slot 30-31, the spindle may be rotated to retract the bolt 9 and incident to such retraction, the beveled tooth 19 will snap over the spring arm 20, the latter then holding the bolt in retracted position and allowing turning of the cap C to remove it. When the cap is again applied, inward push on the spindle 25 either with the key or by hand, will slide said spindle and sleeve 28 inwardly, thereby releasing the spring arm 20 from the tooth 19 and allowing projection of the bolt 9 to its operative position, under the influence of its spring 21.

I wish it understood that any desired lock means may be employed for the purpose of effecting release of the bolt 9, and that the particular bolt-releasing means herein disclosed, is to therefore be considered as illustrative rather than limiting, this being also true of a number of specific details of construction which I have disclosed.

Moreover, it may be stated that if desired, all working parts at the inner side of the cap C may be housed within an appropriate cas- 90 ing (not shown).

The lock structure above described is not restricted to use with caps. By mounting it within an appropriate casing 34 (Fig. 7) and making minor variations, it may be used upon a door D. When such an application is required, the spindle 25 will be provided with an extension 35 provided with a knob 40 at the inner side of the casing 34. Hence, the bolt 9 and the spring arm 20 may be controlled from the interior as well as from the exterior of the door, the proper key being of course necessary in order to operate the lock from the outside.

I claim:

1. An assemblage of the class described comprising a tank filling neck having two opposed arcuate inwardly projecting flanges at its outer end, said flanges being of substantially right angular cross section and having helically pitched edges presented toward the inner end of said neck, the inner sides of said flanges being provided with ratchet teeth; a flanged cap applicable to said neck and having arms to engage said inclined flange edges when the cap is turned; a spring-projected dog mounted on and disposed at the inner side of said cap, said dog being adapted to engage said ratchet teeth to hold the cap against turning in a direction to remove it, and releasing means for said dog operable from the exterior of said cap.

2. An assemblage of the class described comprising a tank filling neck having two opposed arcuate inwardly projecting flanges at its outer end, said flanges being of substantially right angular cross section and having helically pitched edges presented toward the inner end of said neck, the inner side of said flanges being provided with

- 5 ratchet teeth; a flanged cap applicable to said neck and having arms to engage said inclined flange edges when the cap is turned; a spring-projected dog mounted on and disposed at the inner side of said cap, said dog being adapted to engage said ratchet teeth to hold the cap against turning in a direction to remove it, key-operated means rotatably and slidably mounted on said cap and operatively connected with said dog for releasing the latter, and self-applied means for holding said dog in released position, said holding means being releasable by inward sliding of said key-operated means.
- 10 15 3. An assemblage of the class described comprising a flanged cap having a central sleeve projecting outwardly beyond the outer side of the cap, a lock body lying against the inner side of the cap, and provided with a second sleeve passing through and projecting beyond the outer end of said first named sleeve, said body having an opening aligned with said second sleeve, a locking bolt carried by said body, and key-actuated operating means for said bolt carried by said body and having an operating portion extending outwardly through said opening and through and beyond the outer end of said second sleeve.
- 20 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845
5. A lock comprising a body, a spring-projected locking bolt slidably mounted on said body, a spindle slidably and rotatably mounted on said body, said spindle being operatively connected with said bolt for retracting the latter when the spindle is turned in one direction, and a self-applied latch mounted on said body for holding said bolt in retracted position, said latch having a releasing portion positioned to be struck by said spindle when the latter is inwardly slid, thereby releasing said latch and allowing projection of said bolt.
- In testimony whereof I have hereunto affixed my signature.
- WILLOUGHBY F. HOLLISTER.
